ANCHOR STRAP

Lawrence M. Curtiss, Mountainside, N.J., assignor to The Thomas & Betts Co., Incorporated, Elizabeth, N.J., a corporation of New Jersey

Filed Aug. 8, 1963, Ser. No. 76,144

Term of patent 14 years

(Cl. D54—1)

I claim:

The ornamental design for an anchor strap, as shown and described.
